UNITED STATES PATENT OFFICE.

EDWARD C. WALTER, OF NEW YORK, N. Y., ASSIGNOR TO HARRY T. AMBROSE, OF
ORANGE, NEW JERSEY.

TYPE-WRITER.

1,073,573.

Specification of Letters Patent. Patented Sept. 16, 1913.

Application filed September 9, 1910. Serial No. 581,214.

To all whom it may concern:

Be it known that I, EDWARD C. WALTER, a citizen of the United States, residing at New York, in the county of New York and State of New York, have invented certain new and useful Improvements in Type-Writers, of which the following is a specification, reference being had therein to the accompanying drawing.

10 This invention relates to typewriters, and primarily has for an object, in one aspect, the temporary actuation of the spacing structure of the typewriter machine in a direction different from that of its normal 15 travel, whereby a character (such as an exponent), word or line may be printed away from the normal printing point or line.

In another aspect of the invention, the object is to provide controlling mechanism 20 for the actuation of said spacing structure.

A further object is to provide controllable mechanism co-acting with said actuating mechanism, whereby the extent of movement of the spacing structure may be varied at 25 the will of the operator.

A further object is to combine with such controllable mechanism, means whereby the structure may be held in the position to which it may have been actuated.

30 A further object is so to construct and dispose said actuating and controlling mechanisms that, while inactive, the regular operation of the machine is possible.

With these and other objects in view, the 35 invention resides, among other features, in a spacing structure of a typewriter combined with the following instrumentalities, severally and collectively, namely, means for actuating said structure in a direction opposite to its normal travel, mechanism for controlling the degree of movement, devices for varying the movement at the will of the operator, and elements for locking and unlocking the structure in the position 40 to which it may have been actuated under the action of said actuating mechanism for returning it to normal position, and for thereafter controlling it in its normal travel.

45 In the accompanying drawings, I have

illustrated some of the embodiments of my 50 invention and, also, details of preferred forms; but, it is to be understood that the same, each and all, are capable of considerable modification and still be within the spirit of my invention; and, further, it is 55 to be understood that I do not limit myself to such details except in so far as they may be specified in the claims.

In said drawings: Figure 1 is a view in plan of a typewriter—in this instance, a 60 flat-platen typewriter, so-called—with my invention embodied. Fig. 2 is a view in perspective of my carriage-actuating structure, detached from the machine; Fig. 2^a is a diagrammatic view showing the plurality of 65 possible writing positions to which the parts may be relatively moved, it being understood that the machine is adapted to be adjusted to move intermittently a single space, double space, and treble space, according to 70 the adjustment made by the operator; Fig. 3 is a sectional elevation of the line-spacing carriage, on the line 3—3, Fig. 1, locking in the direction of the arrow; and with the side plate of the spacing-mechanism housing removed; the parts in this instance appearing in their unactuated positions; Fig. 4 is a similar view, the parts appearing in the positions they occupy when actuated to effect rearward movement of the line-spacing carriage; Fig. 5 is a similar view of a modified form of adjustable stop-device for controlling the extent of movement of the parts; Fig. 6 is a fragmentary view showing a modified form of mechanism-locking device; and Fig. 7 is a similar view of a somewhat different form of adjustable stop-device for controlling the movement of the parts.

In these drawings, and referring to the 90 form of structure shown in Figs. 1-4, the numeral 1 designates a platen—in this instance shown, by way of example, as a flat-platen—upon which the writing sheet or page A is to be spread out in a flat condition, and be properly retained in position thereon, as by a work-confining device B of appropriate form and characteristics. Ar-

ranged in juxtaposition to the platen is a track-frame C comprising rails or guides 3, 3, preferably provided with a rack 3^a, the purpose of which will presently appear. 5 Adapted to traverse said tracks is a line-spacing-carriage D, and this is designed to travel (during the progressive operation of printing on the sheet) from the rear toward the front. In this instance, therefore, the 10 tracks are the support for said carriage. Superposed on said line-spacing carriage is a letter-spacing carriage E adapted to travel at right-angles to the direction of travel of said line-spacing carriage, and in 15 which is disposed the writing-mechanism F. It will be seen that, by means of these two carriages, the writing-mechanism is adapted to travel in two relatively different directions over the platen. The line-space carriage D includes, at each side, a casing D² in which is housed appropriate carriage-propelling and escapement mechanisms—such, for instance, as those disclosed in United 20 States Patent No. 826,483, dated July 17, 1906. The casings D² of this carriage include rollers d which are adapted to run on the tracks 3 at one side of the racks 3^a. Extending between and journaled in the two casings or housings D² is a drive-shaft 4, 25 upon each end of which is mounted a gear-wheel 5 adapted to mesh with the rack 3^a, aforementioned. A power-spring 6 encompasses the shaft adjacent the gear 5 and, by connecting with said shaft, is adapted to 30 drive the same. Appropriate escapement-mechanism (not shown) for controlling the movement of the carriage is utilized, and may be that revealed in the patent aforementioned. As it forms no part of the present 35 invention, a detailed description thereof is deemed unnecessary. Also fast on the right-hand end of the power-shaft, and spaced from said gear 5, is a toothed wheel 7 adapted to rotate, in the normal travel of 40 the carriage, in a clockwise direction. Normally out of engagement with said toothed wheel but adapted to be actuated into mesh therewith, (by mechanism presently to be described) is a toothed segment 8 supported 45 adjacent the lower end of its actuating-arm 9 fulcrumed at its lower end on a shoulder-screw 9^a and jointed at its upper end at 9^b to the end of a key-lever 10 pivoted at 10^a to the upstanding portion D³ of the right-hand casing or housing D² of the line-spacing carriage. Intermediate of the ends of 50 the key-lever 10 is rotatably mounted thereon a lever-controlling device. In this instance and as illustrated in Figs. 1-4 and 6, it is in the form of a mutilated disk 11 turning on a horizontal axis 11^a and (as shown in Figs. 2 and 4) is provided with a series of abutment-surfaces 12, 13 and 14, and (as shown in Fig. 6) with abutment 55 surfaces 12, 13, 14 and 15, in eccentric ar-

angement relatively to the axis 11^a, the abutment-surface 12 being the nearest and the surface 15 being the remotest from said axis. The purpose of this construction will presently be explained. Adjustably disposed on the upper portion D³ of the line-spacing carriage is a relatively stationary upstanding abutment or post 16 adapted to be engaged by one or another of the abutment-surfaces on the disk 11 when the key-lever 10 is depressed by the operator. 75

In Fig. 5, I have shown a somewhat different form of adjustable lever-controlling stop. In this instance, it comprises a thumb-screw 17 threaded in a boss 18 on the side of 80 the lever 10. The lower end of this screw is designed to impinge against the top of the portion D³ of the line-spacing carriage. By means of this device, any desired degree of adjustment is possible, and thereby the 85 movement of the parts may be controlled to a nicety and within a rather wide range. Similarly, in Fig. 7, I have revealed another modification of lever-controlling device 19, and wherein I utilize the disk shown in 90 Fig. 3; but omit the plurality of distinct abutments and, in lieu thereof, form its operative periphery as a continuous and unbroken surface 20 but eccentric with reference to the axis 19^a of the disk, and any 95 portion of which may be presented (by turning the disk) to abut against the post 16. To control the movement and position of the disk 19, I provide, in this instance, a holding finger 21, pivoted at one end in the 100 side of the key-lever 10 and provided at its opposite end with a bend adapted to engage in one or another of the apertures 19^b in the disk 19. When the latter is thus retained, it will present a predetermined portion of its 105 eccentrically-formed periphery to abut against the post 16 when the key-lever is depressed.

It will be understood that the lever-controlling device may be disposed in locations 110 other than that shown.

Occasionally it is essential or desirable to lock the key-lever in its depressed position whereby the parts and mechanisms which it controls may similarly be locked in 115 their actuated positions. To this end, I dispose a locking-element in such position relatively to said lever that said element may engage therewith or with a part carried thereby, and it may be of many different 120 forms. In the construction disclosed in Fig. 3, I have shown the locking-element in the form of a crimped spring 22 adapted to have one or another of its depressions 22^a engage a pin 23 disposed in the side of the 125 lever 10.

In lieu of the construction shown in Fig. 3, as just described, for locking the key-lever 10 when depressed, I may, as shown in Fig. 6, provide an upstanding spring- 130.

controlled element 24 provided with serrations or teeth 24^a adapted to engage a sharp-edged lug 24^b on the lower edge of the lever 10.

5 Referring again to Figs. 2-4, it will be seen that the shoulder-screw 9^a (already referred to as the fulcrum of the actuating-arm 9) is carried by the angulated arm 25 pivoted at 26 to the side of the housing D², the angular portion 25^a of said arm, beyond the shoulder-screw 9^a, being designed to rest upon the drive-shaft 4 and thereby constitute a stop for all the parts connecting therewith when at rest, that is, before they 15 have been actuated, as will presently be explained.

When the key-lever 10 is depressed by the operator, and which results primarily in actuating the segment-member 8 into mesh with the toothed-wheel 7, there is, initially—while the teeth on said member 8 are moving into engagement with the teeth on wheel 7—some lost motion, and advantage is taken of this to effect the actuation of the 25 following parts: A pawl 27 (which is mounted on a slidable pivot 28 working in an elongated slot 29 in the lower part of the side-plate 30 of the housing D²) is normally in engagement with the rack 3^a, as shown in Fig. 3, and is designed to prevent the line-spacing carriage from being moved backwardly under normal conditions. This pawl carries a headed pin 31 adapted to slide in an elongated slot 32 in a two-piece 35 link 33 fulcrumed at its upper end on a horizontal axis 33^a formed in a stud 34 carried by the lower end of the actuating-arm 9. The two-piece construction of the link 33 is to permit adjustment, whereby the actuation 40 of the pawl 27 may be changed, whenever necessary, as will be understood. The lower portion of the link 33 is provided with the elongated slot 32, already referred to, so that the pawl 27 may be disengaged from 45 the rack by the general-release mechanism (not shown) when it is desired to release the carriage so that it can be moved freely back and forth over the platen.

50 Operation: When the lever 10 is depressed by the operator, it actuates the arm 9 and tends to position the toothed segment 8 in engagement with the toothed-member 7. While this is occurring, the actuating-arm is simultaneously withdrawing the pawl 27 55 from the rack 3^a. As soon as said pawl is disengaged from the rack and the segment 8 has engaged with the member 7, the continued depression of the key-lever 10 will cause the segment 8 to rotate the member 7 60 in a counter-clockwise direction. This will rotate the shaft in the same direction and cause the gear 5 to move the carriage rearwardly. The extent of the movement is controlled by the controlling-devices 11 (Figs. 65 2-4 and 6), 17 (Fig. 5), or 19 (Fig. 17).

The operator predetermines the extent of the movement in accordance with the position at which the printing is to be done; that is to say, whether an exponent-character is to be printed, (as shown by the lower 70 line, Fig. 2^a) in which instance, the controlling-disk 11 is turned to present the abutment-surface 15 in position to engage the post 16; or if an interlineation (such as indicated by the middle line of printing in 75 Fig. 2^a) is to be made, then the disk is turned to present the surface 14 in position; and so on. It is to be understood that the line-spacing carriage is adapted to have variable spacing, as already mentioned. Therefore, 80 I have provided the controlling disk 11 with abutment-surfaces to correspond with the several degrees of spacing so that, in the event the carriage is set for single spacing, it can be actuated rearwardly to correspond 85 with that degree of spacing. If, on the other hand, it is set for double spacing, the disk is similarly set. And if the carriage is adjusted for treble spacing, then the disk will be set correspondingly. In other words, 90 the travel of the carriage is always for an even ratio. For instance, for a single line-space, the carriage would move approximately three-sixteenths of an inch; for double-spacing, the travel would be for six-sixteenths of an inch, and for treble-spacing, the travel would be nine-sixteenths of an inch. Therefore, the teeth in the gear 7 will 95 always stop at the same position, and this enables me to effect a rearward actuation of 100 the writing-mechanism with accurate regard for the degree of spacing that the carriage is set to travel; the rearward movement of the carriage (and, thus, of the writing-mechanism carried thereby) being for a 105 predetermined distance, and this will position the writing-mechanism above the printing point on the platen and a distance therefrom according to how the controlling disk 110 is set. It will be understood, therefore, that the key-controlling member (such as the disk 11) is positioned to govern the extent 110 of depression of the key 10 and, thus, the extent of rearward movement of the carriage according to the degree of spacing 115 for which the carriage has been set to travel forwardly. In consequence, if the carriage-spacing is set for, say, a single-space, the described carriage-actuating mechanism would be positioned to regulate the extent 120 of movement of the key 10 (and of the carriage) within that spacing-distance. If the carriage is set to space the widest of its possible spacing, said carriage-actuating mechanism is correspondingly set to control 125 the rearward movement anywhere within that spacing-distance; the carriage is not permitted to move. In other words, the rearward movement is never beyond the 130

predetermined line-spacing of the carriage. When the key-lever is released, the carriage-driving mechanism (already referred to) will return the carriage to normal position. 5 Ordinarily, the carriage-actuating mechanism will be in inoperative position, and is, in the manner already explained, actuated into operative position by means of the key-lever which, in such instance, becomes a controlling device for the back-spacing mechanism.

It is to be understood that the carriage-driving mechanism (including the power-spring 6) is constantly active to move the carriage forward in the direction of its normal spacing movement. When the carriage-returning-mechanism (including the lever 10) is actuated by the operator, the carriage is moved backward in a direction opposite 20 to such normal travel and is, thus, actuated against the action of said carriage-driving-mechanism. In consequence, the instant the carriage-returning-mechanism becomes inactive—as when the operator removes his 25 finger from the lever 10 to permit it to return to normal position—said carriage-driving-mechanism moves the carriage forward again to the position it occupied when it was actuated backward by said carriage-returning-mechanism. The carriage-driving-mechanism has, therefore, two functions, 30 namely, normally to drive the carriage forward for its spacing movement, and, also, to restore said carriage to position after 35 being moved backward by the carriage-returning-mechanism.

Should it be desired to write more than a single character when the writing-mechanism is actuated, as already explained, 40 and in order that the operator may not be obliged to hold the key-lever 10 in its depressed position during the writing of one or more characters, the locking device (designated 22 in Fig. 3, and 24 in Fig. 6) 45 is utilized and whereby the key-lever 10 will be locked in its depressed position temporarily. By this means, as the key-lever 10 is locked in its depressed position, so also will the writing-mechanism-supporting 50 carriage be locked in the position to which it is actuated. As soon as the said key-lever is released, either by the removal therefrom of the operator's finger, or by disengaging the aforementioned locking 55 device therefrom, the carriage—under the action of the carriage-propelling spring 6—will automatically be returned to normal position—from which it had been actuated—and, thus, be restored to the normal 60 line of writing.

The letter-space carriage E carries a line-finder G (Fig. 1) which is adapted to be actuated to the printing point by the operator through mechanism connecting

with the line-finder-key G². By means of 65 this instrumentality, the operator can determine exactly the point at which a character will be printed, whether the line-spacing carriage is in its actuated or in its normal position.

It will be understood that the carriage-actuating mechanism herein disclosed constitutes my invention, and that, therefore, the same may be regarded as an attachment, to be included in machines, or not, 75 according to the requirements.

As will now be seen, I have herein disclosed a structure which, in one aspect, includes a spacing-carriage adapted to have a normal line-spacing movement on its supporting-tracks, and means—comprising one or another of the forms of instrumentalities already described—for returning said carriage to any of a plurality of predetermined 80 positions relatively to the normal writing line.

Having thus fully described my invention, its construction, and its mode of operation, what I claim and desire to secure by Letters-Patent is:

1. A typewriter including in combination, a stationary member, a traveling member adapted to have a normal spacing movement in relation to said stationary member, and means carried by said traveling member for returning it to any of a plurality of predetermined intermediate 90 positions relatively to the stationary member.

2. In a typewriter, and in combination 100 with a stationary member and a traveling member having a normal spacing movement and including a rotary member, means carried by and movable with said traveling member and connecting with said 105 rotary member for returning the traveling member to any of a plurality of predetermined intermediate positions relatively to said stationary member, and regulable means coacting with said member-returning 110 means for predetermining the extent of return movement of said traveling member.

3. In a typewriter, and in combination 115 with a traveling member adapted to have a normal spacing movement, and a stationary member, of means carried by and movable with said traveling member for returning it relatively to the other member to any of a plurality of predetermined positions, 120 adjustable means for regulating the extent of return movement of said traveling member, and means for returning said traveling member in its returned position.

4. A typewriter including a self-propelled carriage, a stationary member which said carriage traverses, a rotary member included in said carriage, means adapted to

- coact therewith to reverse its rotation, and means coacting with the stationary member to hold said carriage against movement in a direction opposite to that of its normal travel, and adapted to be operated by said member-reversing means to release said carriage.
5. A typewriter including a self-propelled carriage, a stationary member which said carriage traverses, a rotary member included in said carriage, means adapted to coact therewith to reverse its rotation, means coacting with the stationary member to hold said carriage against movement in a direction opposite to that of its normal travel, and adapted to be operated by said member-reversing means to release said carriage, and means for controlling the extent of the reverse movement of said rotary member.
10. 6. In a typewriter, and in combination with a traveling member, and a stationary member, of key-actuated means carried by and movable with said traveling member for moving it relatively to the other member in a direction opposite to that of its normal travel to any of a plurality of predetermined positions, and adjustable means for regulating the extent of movement thereof.
15. 7. In a typewriter, and in combination with a traveling member, and a stationary member, of key-actuated means carried by and movable with said traveling member for moving it in a direction opposite to its normal travel and relatively to the other member to any of a plurality of predetermined positions, and adjustable means for regulating the extent of movement thereof.
20. 8. In a typewriter, and in combination, a spacing carriage adapted to travel in one direction, a stationary member over which said carriage travels, and mechanism carried by and movable with said spacing carriage during its spacing movement and including a key-lever, for positioning said carriage in the direction opposite to its spacing movement to any of a plurality of operative positions.
25. 9. In a typewriter, and in combination, a spacing carriage adapted to travel in one direction, a stationary member over which said carriage travels, mechanism carried by and movable with said spacing carriage and including a key-lever, for positioning said carriage in the direction opposite to its spacing movement to any of a plurality of operative positions, and means co-acting with said mechanism for controlling the extent of the movement of said carriage.
30. 10. In a typewriter, and in combination, a spacing carriage adapted to travel in one direction, a stationary member over which said carriage travels, mechanism supported on and shiftable with said spacing carriage and including a key-lever, for positioning said carriage in the direction opposite to its spacing movement to any of a plurality of operative positions, and adjustable means including a rotatable member having a plurality of engaging faces co-acting with said mechanism for controlling the extent of the movement of said carriage.
35. 11. In a typewriter, and in combination, a spacing carriage adapted to travel in one direction, a stationary member over which said carriage travels, mechanism including a key-lever for positioning said carriage in the direction opposite to its spacing movement to any of a plurality of operative positions, a carriage-retaining element adapted to normally retain said carriage against movement in one direction, and means controlled by said mechanism for actuating said retaining element out of operative position.
40. 12. In a typewriter, and in combination, a spacing carriage adapted to travel in one direction, a stationary member over which said carriage travels, mechanism including a key-lever, for positioning said carriage in the direction opposite to its spacing movement to any of a plurality of operative positions, a carriage-retaining element adapted to normally retain said carriage against movement in one direction, means controlled by said mechanism for actuating said retaining element out of operative position, and means co-acting with said mechanism for controlling the extent of the movement of said carriage.
45. 13. In a typewriter, and in combination, a spacing carriage adapted to travel in one direction, a stationary member over which said carriage travels, mechanism including a key-lever, for positioning said carriage in the direction opposite to its spacing movement to any of a plurality of operative positions, a carriage-retaining element adapted to normally retain said carriage against movement in one direction, means controlled by said mechanism for actuating said retaining element out of operative position, and means, including an adjustable stop-device, co-acting with said mechanism for controlling the extent of the movement of said carriage.
50. 14. In a typewriter, and in combination, a spacing carriage adapted to travel in one direction, a stationary member over which said carriage travels, mechanism including a key-lever, for positioning said carriage in the direction opposite to its spacing movement to any of a plurality of operative positions, a carriage-retaining element adapted to normally retain said carriage against movement in one direction, means controlled by said mechanism for actuating said retaining element out of operative position,

means, including an abutment element and an adjustable stop-device, co-acting with said mechanism for controlling the extent of the movement of said carriage, and means 5 for locking said mechanism when shifted.

15. In a typewriter, and in combination, a writing-mechanism, a supporting carriage therefor adapted to assume a position of rest when said writing-mechanism is operated to 10 print, a support for said carriage, mechanism for effecting travel of said carriage upon said support and including a rotary member, mechanism for positioning said carriage in the opposite direction and including a rotary element disposed in juxtaposition to said rotary member, a normally disengaged device for rotating said element, and means for actuating said device into engagement therewith and effecting its 15 rotation.

16. In a typewriter, and in combination, a writing-mechanism, a supporting carriage therefor adapted to assume a position of rest when said writing-mechanism is operated to print, a support for said carriage, mechanism for effecting travel of said carriage upon said support and including a rotary member, mechanism for positioning said carriage in the opposite direction and 20 including a rotary element disposed in juxtaposition to said rotary member, a normally disengaged device for rotating said element, means for actuating said device into engagement therewith and effecting its 25 rotation, and means normally in engagement with the carriage-support for controlling the movement of said carriage.

17. In a typewriter, and in combination, a writing-mechanism, a supporting carriage 40 therefor adapted to assume a position of rest when said writing-mechanism is operated to print, a support for said carriage, mechanism for effecting travel of said carriage upon said support and including a rotary member, mechanism for positioning said carriage in the opposite direction and including a rotary element disposed in juxtaposition to said rotary member, a normally disengaged device for rotating said element, means for actuating said device into engagement therewith and effecting its 45 rotation, means normally in engagement with the carriage-support for controlling the movement of said carriage, and actuated by said positioning mechanism to disengage said means from said support.

18. In a typewriter, and in combination, a writing-mechanism, a supporting carriage therefor adapted to assume a position of 55 rest when said writing-mechanism is operated to print, a support for said carriage, mechanism for effecting travel of said carriage upon said support and including a rotary member, mechanism for positioning said carriage in the opposite direction and

including a rotary element disposed in juxtaposition to said rotary member, a normally disengaged device for rotating said element, means for actuating said device into engagement therewith and effecting its 70 rotation, and means co-acting with said positioning mechanism for predetermining the movement of said carriage.

19. In a typewriter, and in combination, a writing-mechanism, a supporting carriage therefor adapted to assume a position of rest when said writing-mechanism is operated to print, a support for said carriage, mechanism for effecting travel of said carriage upon said support and including a rotary member, mechanism for actuating said carriage in the opposite direction and including a rotary element disposed in juxtaposition to said rotary member, a normally disengaged device for rotating said element, means for actuating said device into engagement therewith and effecting its 75 rotation, means co-acting with said actuating-mechanism for predetermining the actuated movement of said carriage, and means normally in engagement with the carriage-support for controlling the movement of said carriage.

20. In a typewriter, and in combination, a writing-mechanism, a supporting carriage therefor adapted to assume a position of rest when said writing-mechanism is operated to print, a support for said carriage, mechanism for effecting travel of said carriage upon said support and including a rotary member, mechanism for actuating said carriage in the opposite direction and including a rotary element disposed in juxtaposition to said rotary member, a normally disengaged device for rotating said element, means for actuating said device into engagement therewith and effecting its 80 rotation, means co-acting with said actuating-mechanism for predetermining the actuated movement of said carriage, and means normally in engagement with the carriage-support for controlling the movement of said carriage.

21. In a typewriter, a writing-mechanism sustaining-carriage, a support which said carriage traverses, means for effecting movement of said carriage on its support, and mechanism carried by said carriage and co-operating with said carriage-moving mechanism for returning the carriage to any of a plurality of fractional space positions.

22. In a typewriter, a writing-mechanism sustaining-carriage, a support which said carriage traverses, means for effecting movement of said carriage on its support, mechanism carried by said carriage and co-operating with said carriage-moving mechanism

for returning the carriage to any of a plurality of fractional space positions, and means coacting with said carriage-returning mechanism for controlling movement of the carriage.

23. In a typewriter, a writing-mechanism sustaining-carriage, a support which said carriage traverses, means for effecting movement of said carriage on its support, mechanism carried by said carriage and co-operating with said carriage-moving mechanism for returning the carriage to any of a plurality of fractional space positions, means co-acting with said carriage-returning mechanism for controlling movement of the carriage, and a device co-operating with said controlling-means for limiting its movement.

24. In a typewriter, a writing-mechanism sustaining-carriage, a support which said carriage traverses, means for effecting movement of said carriage on its support, mechanism carried by said carriage and co-operating with said carriage-moving mechanism for returning the carriage to any of a plurality of fractional space positions, means co-acting with said carriage-returning mechanism for controlling movement of the carriage, and means including an adjustable device co-operating with said controlling-means for varying its movement.

25. In a typewriter, a traveling-member having a normal spacing movement, a carriage sustained by and movable with said traveling-member and adapted to traverse the same and, also, to have a normal spacing movement thereon in relation thereto, and means for differentially positioning said traveling-member and the aforementioned carriage which it sustains in a direction opposite to the normal spacing movement of said traveling-member.

26. A typewriter comprising a structure that includes a plurality of carriages, one of which is movable in the direction of line-spacing and another being movable therewith in said line-spacing direction and, also, in the direction of letter-spacing, means for effecting a predetermined differential movement of said structure in a direction opposite to its normal line-spacing, and additional means for moving said structure in the direction of normal line-spacing.

27. In a typewriter including a traveling carriage adapted to move in a forward direction, a support traversed by said carriage, a toothed member carried by said carriage and traveling therewith, means arranged in juxtaposition thereto and adapted to engage said member, mechanism for differentially actuating said engaging means to rotate said member in a direction the reverse of that of its forward-traveling movement and means for driving said carriage in a forward direction, said driving means

operating also to restore said carriage to the position from which it had been moved by said differentially-actuating mechanism after the latter becomes inactive.

28. In a typewriter including a traveling carriage adapted to move in a forward direction, a support traversed by said carriage, a toothed member carried by said carriage and traveling therewith, means arranged in juxtaposition thereto and adapted to engage said member, mechanism for differentially actuating said engaging means to rotate said member in a direction the reverse of that of its forward-traveling movement and means for driving said carriage in a forward direction, said driving means operating also to restore said carriage to the position from which it had been moved by said differentially-actuating mechanism after the latter becomes inactive, and a device co-acting with said mechanism for controlling the extent of its shiftable movement.

29. In a typewriter, a platen, a track juxtaposed thereto and provided with a rack, a carriage adapted to traverse said track, a gear supported in said carriage and meshing with said rack, a toothed member arranged adjacent to said gear, a shaft penetrating said gear and toothed member, carriage-self-propelling mechanism for rotating said shaft to drive said carriage in a forward direction, mechanism for rotating said toothed member in a direction the reverse of its normal rotation with said shaft and including a toothed element, and a key for actuating said toothed element and thereby to rotate said toothed member.

30. In a typewriter, a platen, a track juxtaposed thereto and provided with a rack, a carriage adapted to traverse said track, a gear supported in said carriage and meshing with said rack, a toothed member arranged adjacent to said gear, a shaft penetrating said gear and toothed member, carriage-self-propelling mechanism for rotating said shaft to drive said carriage in a forward direction, mechanism for rotating said toothed member in a direction the reverse of its normal rotation with said shaft and including a toothed element, a key for actuating said toothed element and thereby to rotate said toothed member, and an adjustable stop-device co-acting with said mechanism for controlling the extent of rotation of said toothed member.

31. In a typewriter, a platen, a track juxtaposed thereto and provided with a rack, a carriage adapted to traverse said track, a gear supported in said carriage and meshing with said rack, a toothed member arranged adjacent to said gear, a shaft penetrating said gear and toothed member, carriage-propelling means for rotating said shaft to drive said carriage in a forward

direction, mechanism adapted to overcome the force of said carriage-propelling means for rotating said toothed member in a direction the reverse of its normal rotation 5 with said shaft and including a toothed element, a key for actuating said toothed element and thereby to rotate said toothed member, an adjustable stop-device co-acting with said mechanism for controlling the extent of rotation of said toothed member, and an abutment adapted to be engaged by said stop-device.

32. In a typewriter, a platen, a track juxtaposed thereto and provided with a rack, 15 a carriage adapted to traverse said track, a gear supported in said carriage and meshing with said rack, a toothed member arranged adjacent to said gear, a shaft penetrating said gear and toothed member, 20 means for rotating said shaft to drive said carriage in a forward direction, mechanism for rotating said toothed member in a direction the reverse of its normal rotation with said shaft and including a toothed 25 element, a key for actuating said toothed element and thereby to rotate said toothed member, an adjustable stop-device co-acting with said mechanism for controlling the extent of rotation of said toothed member, 30 and an abutment adapted to be engaged by said stop-device, and means normally in engagement with said rack for controlling the movement of said carriage and shiftable by said mechanism to effect its disengagement 35 from said rack.

33. In a typewriter, the combination of printing-mechanism, a platen, mechanism for actuating one of said elements in a forward direction and under the influence of 40 which said element is normally forced forward, mechanism for differentially returning said element in the opposite direction and against the action of said forward-moving mechanism, and mechanism for rendering 45 said carriage-returning mechanism inactive to permit said forward-moving mechanism to move said element forward immediately upon said carriage-returning-mechanism becoming inactive.

50 34. In a typewriter, the combination of printing-mechanism, a platen, mechanism for actuating one of said elements in a forward direction and under the influence of which said element is normally forced forward, mechanism for differentially returning 55 said element in the opposite direction and against the action of said forward-moving mechanism, and mechanism for rendering said carriage-returning mechanism inactive to permit said forward-moving mechanism to move said element forward immediately upon said carriage-returning-mechanism becoming inactive, and means co-acting with said element-returning-mechanism 60 for governing the extent of its movement

and, thereby, of the traveling element relatively to the other element.

35. In a typewriter, the combination of printing-mechanism, a platen, mechanism for actuating one of said elements in a forward direction and under the influence of which said element is normally forced forward, mechanism for differentially returning said element in the opposite direction and against the action of said forward-moving mechanism, and mechanism for rendering 70 said carriage-returning mechanism inactive to permit said forward-moving mechanism to move said element forward immediately upon said carriage-returning- 75 mechanism becoming inactive, and means co-operating with said element-returning mechanism for varying the movement of said element.

36. In a typewriter, a carriage adapted to have a normal spacing movement, means for actuating the carriage to travel in one direction, and a differential carriage-positioning mechanism supported on and movable with said carriage to return it to any 80 of a plurality of intermediate positions relatively to the normal printing line.

37. In a typewriter, a carriage having a variable spaced movement normally in one direction, means for actuating said carriage 95 in said normal direction, mechanism for controlling the normal travel of said carriage, and a normally inactive carriage-positioning mechanism supported on and movable with said carriage and actuatable for 100 moving it in the opposite direction, said carriage-actuating mechanism being constantly active and operating to move said carriage forward when said carriage-positioning mechanism becomes inactive.

38. In a typewriter, a carriage having a variable spacing movement normally in one direction, means for actuating said carriage in said normal direction, mechanism for controlling the normal travel of said carriage, and a normally inactive variable carriage-positioning mechanism supported on and movable with said carriage and actuatable for moving it in a direction opposite to its normal travel, said carriage-actuating 110 mechanism being constantly active and operating to move said carriage forward when said carriage-positioning mechanism becomes inactive.

39. A carriage-positioning mechanism for 115 a typewriter, comprising a toothed member adapted to normally rotate in one direction, a toothed element adapted to engage therewith to actuate it in the opposite direction, and a key-actuated mechanism supported in 120 juxtaposition to and traveling with said toothed member for positioning said toothed element into and out of engagement with said toothed member.

40. A carriage-positioning mechanism for 125

5 a typewriter, comprising a toothed member adapted to normally rotate in one direction, a toothed element adapted to engage therewith to actuate it in the opposite direction, 5 a key-actuated mechanism supported in juxtaposition to and traveling with said toothed member for positioning said toothed element into and out of engagement with said toothed member, and a stop-device 10 for controlling said key-actuated mechanism.

41. A carriage-positioning mechanism for a typewriter, comprising a toothed member adapted to normally rotate in one direction, 15 a toothed element adapted to engage therewith to actuate it in the opposite direction, a key-actuated mechanism for positioning said toothed element into and out of engagement with said toothed member, a stop-device 20 for controlling said key-actuated mechanism, and a carriage-retaining device juxtaposed to said toothed element and controlled thereby in its movement.

42. A carriage-positioning mechanism for 25 a typewriter, comprising a toothed member adapted to normally rotate in one direction, a toothed element adapted to engage therewith to actuate it in the opposite direction, a key-actuated mechanism for positioning 30 said toothed element into and out of engagement with said toothed member, a stop-device for controlling said key-actuated mechanism, a carriage-retaining device juxtaposed to said toothed element and controlled thereby in its movement, and means 35 for movably supporting said toothed element and retaining device.

43. A carriage-positioning mechanism for 40 a typewriter, comprising a toothed member adapted to normally rotate in one direction, a toothed element adapted to engage therewith to actuate it in the opposite direction, a key-actuated mechanism supported in juxtaposition to and traveling with said 45 toothed member for positioning said toothed element into and out of engagement with said toothed member, a stop-device for controlling said key-actuated mechanism, and provided with an abutment surface.

44. A carriage-positioning mechanism for 50 a typewriter, comprising a toothed member adapted to normally rotate in one direction, a toothed element adapted to engage therewith to actuate it in the opposite direction, 55 a key-actuated mechanism for positioning said toothed element into and out of engagement with said toothed member, and a stop-device for controlling said key-actuated mechanism provided with a plurality of 60 abutment-surfaces and rotatable to present one or another of said surfaces in operative position.

45. A carriage-positioning mechanism for 65 a typewriter, comprising a toothed member

adapted to normally rotate in one direction, a toothed element adapted to engage therewith to actuate it in the opposite direction, a key-actuated mechanism for positioning said toothed element into and out of engagement with said toothed member, a stop-device for controlling said key-actuated mechanism provided with a plurality of abutment-surfaces and rotatable to present one or another of said surfaces in operative position, and a mechanism-locking device for retaining said carriage positioning mechanism in one or another of its operated positions.

46. A typewriter including in combination, a stationary member, a traveling member adapted to have a normal spacing movement in relation to said stationary member, means connected with said traveling-member for returning it to a predetermined position relatively to the stationary member, adjustable means for regulating the extent of return movement of said traveling-member, and means connected with said traveling-member and operating both to drive the 90 traveling-member forward normally and to restore it to the position from which it had been returned by said returning-mechanism.

47. A typewriter including in combination, a stationary member, a traveling member adapted to have a normal spacing movement in relation to said stationary member, means carried by said traveling member for returning it to any of a plurality of predetermined intermediate positions relatively 95 to the stationary member, and adjustable means for regulating the extent of return-movement of said traveling member.

48. A typewriter including in combination, a stationary member, a traveling member adapted to have a normal line-spacing movement in relation to said stationary member, means supported on and movable with said traveling member for returning it to any of a plurality of predetermined intermediate positions relatively to the stationary member, and adjustable means for regulating the extent of return-movement of said traveling member.

49. A typewriter including in combination, a carriage normally movable in the direction of line-spacing, a second carriage mounted on and movable with said first-mentioned carriage in the direction of line-spacing and movable also in the direction of letter-spacing, means for effecting a predetermined differential movement of said line-spacing carriage, and means for moving said carriage back to the position from which it has been returned.

50. A typewriter including in combination, a carriage normally movable in the direction of line-spacing, a second carriage mounted on and movable with said first-mentioned carriage in the direction of line- 130

spacing and movable also in the direction of letter-spacing, means for effecting a pre-determined differential movement of said line-spacing carriage in a direction opposite to the normal line-spacing travel, and means for effecting a movement of said carriage in the direction of normal line-spacing.

In testimony whereof I affix my signature in presence of two witnesses.

EDWARD C. WALTER.
